UNITED STATES PATENT OFFICE.

JOSEPH F. CHMELIR, OF ST. LOUIS, MISSOURI.

VENTILATING-WINDOW.

SPECIFICATION forming part of Letters Patent No. 791,248, dated May 30, 1905.

Application filed March 11, 1905. Serial No. 249,570.

To all whom it may concern:

Be it known that I, JOSEPH F. CHMELIR, a citizen of the United States, residing in the city of St. Louis, in the State of Missouri, have invented certain new and useful Improvements in Ventilating-Windows, of which the following is a full, clear, and exact description, reference being had to the accompanying drawings, forming part of this specification.

My invention relates to that class of ventilating-windows used in churches and other similar buildings and in which are used outer storm-panes and inner panes usually of cathedral-glass that are protected by the storm-panes.

Figure I is an elevation of my improved window looking at the outer side thereof. Fig. II is a vertical section taken through my window set in the window-frame of a building. Fig. III is an enlarged view of parts of the window at the point of pivotal attachment of the pane-casement to its supporting-frame. Fig. IV is a perspective view of a fragment 25 of the pane-casement at the location of one of its pivots. Fig. V is a perspective view of one of the lower corners of my window.

1 designates the supporting-frame of my window, which is of rectangular shape and 30 formed entirely of angle-iron without any joints being present between the corners of the frame either at its sides or at its top or bottom. At the outer side of the supporting-frame is an inwardly-extending flange 2, that extends 35 continuously across the top of the frame and downwardly therefrom at each side to points at approximately the vertical center of the frame, as seen in Figs. I and II. At the inner side of the frame is a flange 3, that extends continuously across the bottom of the frame and upwardly therefrom at each side to points approximately at the vertical center of the frame. (See Figs. II and V.) Midway of the height of the supporting-frame 1 are 45 pivot-stud slots 4, that are located between the lower ends of the flanges 2 and the upper ends of the flanges 3. (See Fig. III.) The supporting-frame 1 is adapted to be mounted in a window-frame A, as seen in Fig. II, and 50 it is surmounted by a channel-shaped retain-

ing-strip 5, that is secured to the top of the supporting-frame and enters into the window-frame A. The supporting-frame may be secured at the bottom to the window-frame by any suitable means, such as screws 6.

B designates a rectangular casement that is constructed of angle-iron and which is swingingly supported within the supporting-frame 1 by pivot-studs 7, projecting from the sides of the casement and seated in the notches 4 in the supporting-frame sides. The casement B consists of a continuous main flange 8, by which the studs 7 are carried and which fits immediately within the supporting-frame 1, and an inwardly-extending continuous flange 65 8', located at the inner side of the casement. (See Figs. I, II, IV, and V.)

C designates a rectangular detachable stop of angle shape in cross-section and consisting of a flange 9, fitting against the casement-flange 8, and a flange 10, projecting inwardly within the casement, said last-named flange being located at the outer side of the stop. The stop C is located remote from the inwardly-extending flange 8' of the casement B, 75 and it is secured to the casement by bolts 11 located at intervals and passing through said members.

12 designates an inner pane of glass set into the casement B and resting against its inwardly-extending flange 8', said inner pane being preferably surrounded by a rectangular metallic rim 13. This inner pane is held within the casement due to its resting against the casement-flange 8' and the bearing of the stop 85 C thereagainst.

14 designates an outer or storm pane of glass set into the casement and resting against the inwardly-extending flange 10 of the detachable stop C. This outer pane is held within the casement against said stop-flange by a layer 15 of putty.

When the panes 12 and 14 are to be set into the casement B, the stop C is removed from the casement by withdrawing the bolts 11, so 95 that said stop may be lifted from the casement. The inner pane 12 is then set in place against the casement-flange 8' and the stop C is again introduced and secured by the bolts 11. The outer pane 14 is then seated in the 100

casement to rest against the stop-flange 10 and is secured by the application of the layer of putty at the joint between the casement and the edges of said pane. Thus a very secure means of mounting of the inner and outer panes is attained. It will be seen that the panes 12 and 14 may both be readily extracted from the casement at any time, as only the single layer of putty needs to be removed, when the outer pane 14 may be lifted from the casement, and thereafter it is only necessary to withdraw the bolts 11 to extract the stop C in order to permit the removal of the inner pane 12.

15 For the purpose of avoiding breakage of the panes of glass in the casement I apply to the supporting-frame flanges 2 and 3 a bumper-strip 16, (see Figs. II and V,) against which the casement C strikes when it is swung into closed position.

17 represents hoods or rain-guards secured to the sides of the supporting-frame 1 at the outer edges thereof and at the points of pivotal support of the casement in said frame, these guards being designed to prevent the beating of rain through the joints at the points of pivotal support of the casement.

I claim as my invention—

1. In a ventilating-window, the combination of a rectangular supporting-frame, a rectangular casement swingingly mounted in said frame and provided at its inner side with an inwardly-extending flange, an inner pane

seated in said casement and resting against said inwardly-extending flange, a rectangular 35 detachable stop seated in said casement, and an outer pane resting against said stop, substantially as set forth.

2. In a ventilating-window, the combination of a rectangular supporting-frame, a rectangular 40 casement swingingly mounted in said frame and provided at its inner side with an inwardly-extending flange, an inner pane seated in said casement and resting against said inwardly-extending flange, a rectangular 45 detachable stop seated in said casement, and an outer pane resting against said stop; said stop consisting of a flange fitting against said casement and a flange extending inwardly, therefrom at the back of said outer pane, substantially 50 as set forth.

3. In a ventilating-window, the combination of a rectangular supporting-frame, a rectangular 55 casement swingingly supported in said frame and consisting of a main flange and an inwardly-extending flange, an inner pane resting against said inwardly-extending flange, a rectangular stop fitting within said casement against its main flange, bolts detachably securing said stop to said casement and an outer 60 pane resting against said stop, substantially as set forth.

JOS. F. CHMELIR.

In presence of—

BLANCHE HOGAN,

NELLIE V. ALEXANDER.
